UNITED STATES PATENT OFFICE.

EDWARD L. DUNN, OF WORCESTER, MASSACHUSETTS, ASSIGNOR, BY MESNE ASSIGNMENTS, TO STANDARD PLUNGER ELEVATOR COMPANY, OF WORCESTER, MASSACHUSETTS, A CORPORATION OF MASSACHUSETTS.

ELEVATOR-DOOR-LOCKING MECHANISM.

1,223,157.

Specification of Letters Patent. Patented Apr. 17, 1917.

Application filed May 25, 1912. Serial No. 699,693.

To all whom it may concern:

Be it known that I, EDWARD L. DUNN, a citizen of the United States, residing at Worcester, in the county of Worcester and State of Massachusetts, have invented certain new and useful Improvements in Elevator-Door-Locking Mechanisms, of which the following is a full, clear, and exact specification.

- 10 This invention relates to elevator door locking mechanism, and has particular reference to means for preventing the opening of an elevator well door except when the car is at rest opposite the door.
- 15 The invention is especially intended for use in connection with power operated dumb waiter systems, wherein dumb waiter cars are required to at all times operate as high as 600 feet per minute. In such systems, it is necessary, in order to protect the attendants, to prevent them from opening the hatchway doors except when the car has stopped at their floor to be loaded or unloaded. Various means for controlling the 25 doors of dumb waiter and other elevator systems have heretofore been devised, wherein, so far as I am aware, the doors have been normally held locked, and automatically unlocked either as the car passed each floor, or 30 automatically unlocked only when the car stopped at the floors.

According to this invention, I have devised a door locking mechanism in which the door when closed is not locked, but which is 35 automatically locked as soon as an attendant tries to open it, unless the car is stopped at that floor, whereupon the lock controlling devices coöperate with the car in such manner as to prevent the lock from operating, 40 and thereby permit the door to be opened.

In the accompanying drawings, Figure 1 is a plan view of a portion of an elevator system equipped with this invention;

Fig. 2 is an elevation taken along the line 45 2, 2 of Fig. 1, viewed in the direction of the arrow;

Fig. 3 is an elevation showing the inven-

tion in normal condition with the door closed and unlocked;

Fig. 4 shows the door partially raised and 50 locked;

Fig. 5 shows the unlocked position with the door partially raised and the latch held out of engagement by coöperation with the car; and

55 Figs. 6 and 7 are detail views, respectively, of the latch and the actuating cam.

Referring to the drawings, 1 represents the hatchway of an elevator containing the car 2 and closed by a door 3, herein shown as 60 a vertically movable door sliding between guides 4 and carried by the building. I do not restrict myself to the particular form of vertically sliding door herein shown, as the invention is applicable without material modification, or any departure from the invention, to either horizontally sliding doors or hinged doors, such applications of the invention not being necessary to be illustrated herein and being covered by the attached 65 claims. The door 3 is normally unlocked, and is provided with a keeper 6, which is engaged by a latch 7 pivoted on the door frame at 8, to hold the door locked. The pivot 8 carrying latch 7 consists of a shaft, 70 to which latch 7 is pinned, and also pinned on this shaft 8 is an arm 9 carrying the roller 10, the roller 10 and arm 9 being positioned so as to swing into and out of the path of movement of a cam or track 11 carried by the car 2. When the lever 9 and roller 10 are in the position shown in Fig. 3, the door is unlocked and cam 11 passes up and down the hatchway with the car without striking the rollers 10. Mounted loosely on 75 the shaft 8 is a cam 12 (Fig. 7) having the inclined surface 13, and the flat surface 14, and connected through a spiral spring 15 with the shaft 8 or the latch 7. 16 is a stud or roller carried by the door, herein shown as mounted on the upper end of the plate or casting which carries the keeper 6. 17 is a coil spring attached at one end to the lever 9 or shaft 8 and at the other end to the bearing

18 in which the shaft 8 is mounted and tending normally to hold the roller 10 and the latch 7 in the position shown in Fig. 3. In Fig. 3, the normal closed position of the door is shown, wherein the keeper 6 is some distance below the lower end of the latch 7 and the roller 10 is out of the path of movement of the cam 11. Also in this position, the cam surface 13 rests on the stud or roller 16. If the door is pushed upward, the effect is to cause the stud 16 to ride up on the cam 12 to the flat portion 14, thereby throwing the parts into the position shown in Fig. 2, spring 15 being strong enough to overcome spring 17. The door is thus locked against further upward movement because of the latch 7 coming into the path of the keeper 6, while the arm 9 and roller 10 are thrown outward to the position shown in Fig. 4. It will thus be seen that the door is locked as soon as the attendant commences to move it upward. If, however, the cam 11 is opposite the roller 10, it will be seen that the latch 7 will not be thrown into the path of the keeper 6, so that the door can be opened, the stud 16 moving away from the cam 12 and the keeper 6 passing over the cam 12 both during the opening movement of the door and the closing movement. 19 represents an adjustable stop mounted on the end of shaft 8 which can be set to regulate the throw of spring 17, for the purpose of setting the roller 10 the proper distance from the vertical path of cam 11, as shown in Fig. 2. The cam 12 has a certain amount of lost motion between it and latch 7, before it operates latch 7, this being provided for by the teeth 22, 23 which are cut away to the desired extent.

Having thus described my invention, I declare that what I claim as new and desire to secure by Letters Patent is:—

1. The combination with an elevator door, of normally unlocked locking means actuated to locking position by opening movement of the door, and means for holding said means unlocked when the elevator car is at said door.

2. The combination with an elevator car, of a door, normally inoperative means controlled by the door for locking the door against full opening while permitting a limited movement thereof, and means carried by the car for holding said locking means inoperative.

3. The combination with an elevator car, of a normally free door, means for locking the door upon opening movement thereof, and means carried by the car for holding said locking means inoperative when the door is opened.

4. The combination with an elevator car, of a normally free door, a keeper carried by

said door, a latch controlled by opening movement of said door to engage said keeper 65 to lock the door, and means carried by the car for preventing engagement of said keeper and said latch.

5. The combination with an elevator car, of a normally free door, locking means operated by movement of said door to prevent full opening, and means carried by the car and coöperating with said locking means to prevent operation of said locking means.

6. A door locking mechanism comprising 75 a keeper, and a latch, one being attached to the door and the other to the casement and being normally disengaged, means for throwing the latch into the keeper upon movement of the door, and means independent of 80 the door for holding the latch out of the keeper when the door is to be opened.

7. A door locking mechanism comprising a keeper, and a latch, one being attached to the door and the other to the casement and 85 being normally disengaged, means for throwing the latch into the keeper upon movement of the door, and means controlled by a movable car opposite the door for holding the latch out of the keeper when the door is to 90 be opened.

8. The combination with a car, of a door, means controlled by movement of the door for locking it against opening, and means carried by the car for rendering said locking 95 means inoperative.

9. A door locking mechanism comprising a keeper, and a latch, one being attached to the door and the other to the casement, a spring normally holding the latch out of engagement with the keeper, means operated by the door for throwing the latch into the keeper against said spring, and a spring connecting said means with the latch and stronger than said first spring.

10. A door locking mechanism comprising 100 a keeper, and a latch, one being attached to the door and the other to the casement and being normally disengaged, a rock shaft carrying said latch, an arm carried by said rock 110 shaft, a car having means for limiting movement of said latch toward the keeper, and means effective upon an opening movement of the door for moving said latch into the keeper.

11. A door locking mechanism comprising a keeper, and a latch, one being attached to the door and the other to the casement, a rock shaft carrying said latch, an arm carried by said rock shaft, a car having means for limiting movement of said latch toward the keeper, means effective upon an opening movement of the door for moving said latch into the keeper, and a spring operating connection between said means and the latch.

12. A door locking mechanism compris-

ing a keeper, and a latch, one being attached to the door and the other to the casement, and being normally disengaged, means operated by movement of the door from closed 5 position for throwing the latch into the keeper to stop the door, means engageable with an elevator car for preventing throwing of the latch into the keeper, and a

yielding connection between said means and the latch.

In testimony whereof I affix my signature in presence of two witnesses.

EDWARD L. DUNN.
